UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL MACHINE.

Application filed May 7, 1927. Serial No. 189,509.

This invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter elevated and returned through distributing mechanism to the magazine from which they started. More particularly, it relates to that class of linotype machines equipped with a plurality of magazines mounted in or carried by a so-called "shift-frame," which is movable 10 upwardly and downwardly in the machine frame to bring one or another of the magazines into operative relation to the assembling and distributing devices. In the commercial machines of this type, the shifting of the magazines is accomplished by means 15 of screw mechanism operated by a hand crank conveniently located at the front of the machine. While this arrangement is thoroughly practical, the operation has always been slow and tedious and more or less 20 laborious.

The present invention contemplates the use of power for raising and lowering the magazines, and the mechanism herein provided presents many advantages over prior devices, besides being readily applicable to the standard commercial machines. In the preferred embodiment illustrated, the inclined lay shaft, ordinarily employed for turning the magazine elevating screw, is operatively connected to a compact, reversible gear mechanism driven by the well-known intermediate shaft and controlled directly from the front of the machine by means of a clutch shifting rod rotatably mounted in the fore-and-aft assembler drive shaft. Moreover, the customary bevel gears used for driving the said assembler shaft serve as constituents of the proposed mechanism, thereby simplifying the construction and reducing the cost of manufacture.

In the accompanying drawings, the inven-

tion has been shown merely in preferred form and by way of example, and obviously many changes and variations may be made 55 therein and in its mode of adaptation which will still be comprised within its spirit. It is to be understood, therefore, that the invention is not limited to any specific form or embodiment except in so far as such limitations are specified in the claims.

Referring to the drawings:

Fig. 1 is a side elevation of a portion of a linotype machine equipped with the present improvements;

Fig. 2 is a horizontal section taken on the line 2—2 of Fig. 1;

Fig. 3 is a vertical section taken on the line 3—3 of Fig. 2; and

Fig. 4 is a detail transverse section taken 70 on the line 4—4 of Fig. 3.

The several magazines A are mounted upon the separate base frames A¹ conjointly constituting a "shift frame" which is arranged to be moved upwardly and downwardly in the fixed machine frame to bring any selected one of the magazines into operative relation to the assembler entrance B and the magazine entrance C, the latter leading from the distributor D and serving to 75 conduct the matrices to their proper magazine channels. The release of the matrices from the operative magazine is controlled in the usual way from the keyboard E through the medium of reeds and levers 80 not shown. The magazine shift frame (Fig. 1) is carried by the sliding plunger A², which is mounted in the sleeve O secured rigidly to the main frame, and which engages the screw F geared at its lower end 85 to the inclined lay shaft F¹, the arrangement being such that the rotation of said shaft in one direction or the other turns the screw in a corresponding direction and causes it to raise or lower the shift frame. At its forward end, the lay shaft F¹ (see Fig. 2) is provided with the horizontal extension F² supported in suitable bearings secured to the intermediate bracket O¹. Also supported in suitable bearings of the intermediate bracket 90 O¹ is the fore-and-aft assembler drive shaft G, common to all machines of the present type, and which is arranged above and in close proximity to the keyboard E. This

shaft G is provided at its forward end with the usual pulley G¹ for driving the assembling devices, and at its rear end with the beveled gear G² meshing with the similar gear H¹ keyed to the constantly driven "intermediate" shaft H.

In order to insure transverse registration of the individual magazines with the assembler entrance B and the magazine entrance 10 C, two pairs of gauge bars are provided and arranged at opposite sides of the magazines, the bars J, J¹ of each pair being notched at j and rigidly connected together by an intervening piece J². These bars are supported at their lower ends upon the plain aligning surfaces J³ of the fixed machine frame and present their upper ends in position to engage the under sides of the aligning lugs A³ projecting laterally from the opposite sides of the magazine base frames A¹ at both ends thereof. When any selected magazine is brought into operative position, the aligning lugs A³ of its base frame will be caused to bank upon the gauge bars J, 20 J¹, which thus arrest the magazine in proper transverse registration with the assembler entrance B and the magazine entrance C, respectively. In providing for the engagement of the gauge bars J, J¹ with the aligning lugs A³, the former are arranged to slide forwardly and rearwardly on the fixed aligning surfaces J³ so as in one position to stand clear of the aligning lugs during the shifting of the magazines, and in the other position to stand beneath the lugs of the selected magazine base frame, the movement of the gauge bars being controlled by the hand lever J⁴ through the pair of arms J⁵ rising from the rock shaft J⁶ and operatively connected at their upper ends to the bar connecting piece J². With this arrangement, when it is desired to substitute another of the several magazines for the one being used, the shift frame is raised slightly 30 to relieve the gauge bars of the weight of the operative magazine, so that, by depressing the hand lever J⁴, the gauge bars may be drawn forwardly against the tension of their actuating springs j¹ out of the path of the magazine aligning lugs A³. After the magazines have been raised or lowered to approximately the position desired, the handle J⁴ is released to allow the bars to resume their active position beneath the aligning lugs of the magazine selected, whereupon the shift frame is lowered slightly until the lugs engage the bars, which thus support the selected magazine in operative position.

The parts so far described, except as hereinafter specified, are or may be the same in form and mode of operation as those embodied in the commercial Model 8 linotype and in themselves constitute no part of this invention.

According to the present invention, the

raising and lowering of the magazines is accomplished by means of a reversible gear mechanism which is arranged directly behind the fore-and-aft assembler pulley shaft G, the latter, in the present instance, being 70 made hollow or tubular in form to afford direct access to said mechanism from the front of the machine. As best shown in Figs. 2 and 3, the proposed gear mechanism comprises the driving gear H¹, the pulley shaft gear G² meshing therewith, both before referred to, and a bevel gear H² to pair off with the gear H¹ and also meshing with the gear G². The gears H¹, H² thus constitute the reversing gears and rotate 75 constantly in opposite directions, the gear H² being loose on the intermediate shaft H and receiving its motion from the pulley shaft gear G², and the gear H¹ being keyed to the intermediate shaft H and thus rotated directly thereby. A driving connection between the lay shaft F¹ and either one of the reversing gears is effected by a clutch member K loosely mounted for axial movement on the intermediate shaft H and arranged 80 between said gears for engagement therewith. The clutch member K is provided with a bevel gear K¹ which meshes with a similar gear F³ fastened to the free end of the horizontal extension F² of the lay shaft; it being noted (see Fig. 2) that the gear K¹ is splined, as at k, to the clutch member K so that the axial movement of the latter may take place without disturbing the meshed relation of these gears. At one end, 85 the clutch member K is provided with a friction clutch surface k¹ adapted to engage a corresponding surface h of the reversing gear H² when the clutch member is shifted to the left; and at its opposite end it is formed with a positive or jaw clutch portion k² which is intended to engage a corresponding clutch portion h¹ secured to the driving gear H¹ when the clutch member is shifted to the right. Employment of the 90 two types of clutches is desirable, since the friction clutch on the one hand, while sufficient to overcome the relatively light resistance in lowering the magazines, permits the magazine selected to be properly arrested in operative position by the banking of its aligning lugs A³ on top of the gauge bars J, J¹ without undue strain on the parts or binding of the gears, while the jaw clutch, on the other hand, because of its delicate control, is better suited to overcome the relatively heavy load imposed upon the parts in raising the magazines.

The operation of the clutch member K is effected directly from the front of the machine by means of a rod K² rotatably mounted in the fore-and-aft pulley shaft G. The rod K² is provided at its forward end with a small handle K³ located within easy reach of the operator and, at its opposite or 125

inner end, with a fixed collar or crank K^4 which is pivoted, as at K^7 , to a fork K^5 arranged to engage an annular groove k^3 formed in the clutch member K . Normally, and when the handle K^3 occupies the vertical position shown, the clutch member K stands disengaged from both gears H^1 , H^2 and, if desired, a detent K^6 (Fig. 3), seated in the fork K^5 and engaging a corresponding recess formed in the pivot pin K^7 , may be employed to maintain the clutch member yieldingly in such disengaged or neutral position. By throwing the handle K^3 to the right, the collar or crank K^4 will 10 shift the clutch member K toward the gear H^2 and, as the friction clutch surface k^1 engages the opposing clutch surface h , a driving connection will be established between the intermediate shaft H and the lay shaft F^1 through the medium of the fore-and-aft pulley shaft gear G^2 , this connection causing the lay shaft to be turned in one direction to lower the magazine shift frame. Conversely, when the control handle is 15 thrown to the left, the jaw clutch member k^2 is brought into engagement with the co-operating clutch member h^1 of the reversing gear H^1 , and the driving connection thus established causes the lay shaft to be driven directly by the intermediate shaft H in the opposite direction to raise the magazine shift frame. As a precaution against damage that might be caused by some obstruction in the path of the magazines or other moving parts when the jaw clutch surfaces are 20 engaged, it is proposed to incorporate in the driving connections some sort of slip joint or coupling F^4 , such as that indicated in Fig. 1 and as applied to the inclined portion 25 of the lay shaft F^1 .

The operation of the parts will now be clear: Assuming the upper magazine to be in operative position and that one of the lower magazines is selected for use, pressure is first applied with one hand to the lever J^4 which controls the movement of the gauge bars J , J^1 and, with the other hand, the control handle K^3 is rocked to the left to engage the positive clutch members h^1 and k^2 30 to elevate the magazines. As the magazines start to move up, the gauge bars are freed from the weight of the magazine structure and continued hand pressure on the lever J^4 withdraws them to their inactive position 35 out of the path of the lugs A^3 . When the magazine selected has reached a point slightly above its normal operative position, the lever J^4 is released and the actuating springs j^1 draw the gauge bars back to their active 40 position with their upper ends beneath the aligning lugs of said magazine. The control handle K^3 is now rocked to the right to engage the friction clutch surfaces h and k^1 to lower the magazines until the aligning lugs A^3 of the selected magazine settle down 45

upon the tops of the gauge bars J , J^1 , at which time the control handle is returned to its central position to place the clutch member K in neutral. As the magazines are thus lowered, the friction clutch surfaces h , k^1 50 serve, by the slippage which they permit, to prevent any damage to or any unnecessary strain upon the parts. When a change of magazines necessitates a lowering of the magazines, the latter must first be raised 55 slightly in the manner just stated, to free the gauge bars J , J^1 , preparatory to their withdrawal. The operation of the control handle is then reversed to engage the friction clutch surfaces h , k^1 which should be 60 held in engagement until the desired magazine is arrested by the gauge bars, the latter meanwhile having been released in time to resume their normal position for engagement with the aligning lugs A^3 of the magazine selected. 65

Having thus described my invention, its construction and mode of operation, what I claim and desire to secure by Letters Patent of the United States is:

1. In a linotype machine, the combination with a plurality of magazines, a shift frame wherein the magazines are mounted and a screw for raising and lowering the shift frame to bring a selected magazine 95 into operation position, of means for rotating the screw comprising the intermediate shaft, the assembler drive shaft, a lay shaft geared to the screw, and intermediate reversible gear mechanism for connecting the lay shaft directly with the intermediate shaft or with the assembler drive shaft, whereby the screw may be rotated in one direction or the other, as desired. 100

2. In a linotype machine, the combination with a plurality of magazines, a shift frame wherein the magazines are mounted, and a screw for raising and lowering the shift frame to bring a selected magazine into operation position, of means for rotating the screw comprising the intermediate shaft, the assembler drive shaft, a lay shaft geared to the screw, a clutch member geared to the lay shaft, and means for connecting and disconnecting said clutch member with and 110 from the intermediate shaft and the assembler drive shaft to effect the rotation of the screw in one direction or the other. 115

3. In a linotype machine, the combination with a plurality of magazines, a shift frame wherein the magazines are mounted, a screw for raising and lowering the shift frame to bring a selected magazine into operative position, the intermediate shaft, and the assembler drive shaft geared thereto, of a reversing gear mechanism for rotating the screw including a gear driven from the assembler shaft in one direction and a corresponding gear driven directly from the intermediate shaft in the opposite direction, a 120 125

4
lay shaft geared to the screw, and a hand-controlled clutch member geared to the lay shaft and shiftable to connect and disconnect the lay shaft with and from said reversing gears, as desired.

5. In a linotype machine, the combination with a plurality of magazines, a shift frame wherein the magazines are mounted, a screw for raising and lowering the shift frame to bring a selected magazine into operative position, the intermediate shaft, and the assembler drive shaft geared thereto, of a reversing gear mechanism for rotating the screw including a pair of oppositely rotating gears, one driven from the pulley shaft and loose on the intermediate shaft, and the other fast to the intermediate shaft, a lay shaft geared to the screw, a clutch member geared to the lay shaft, and means for engaging the clutch member with either of the oppositely rotating gears, as desired.

6. In a linotype machine, the combination with a plurality of magazines, a shift frame wherein the magazines are mounted and a screw for raising and lowering the shift frame to bring a selected magazine into operative position, of means for rotating the screw comprising the transverse intermediate shaft, the fore-and-aft assembler drive shaft, a lay shaft geared to the screw, and a reversible gear mechanism mounted directly upon the intermediate shaft and arranged adjacent the rear end of the assembler shaft for connecting the lay shaft with the intermediate shaft, whereby the screw may be rotated in one direction or the other, as desired.

7. In a linotype machine, the combination with a plurality of magazines, a shift frame wherein the magazines are mounted and a screw for raising and lowering the shift frame to bring a selected magazine into operative position, the transverse intermediate shaft, hollow fore-and-aft assembler drive shaft geared thereto, a reversible gear mechanism for connecting the screw with the intermediate shaft, and means mounted in the pulley shaft for controlling said reversible gear mechanism, whereby the screw may be rotated in one direction or the other, as desired.

8. In a linotype machine, the combination of a plurality of magazines, a shift frame wherein the magazines are mounted, a screw for raising and lowering the shift frame to bring a selected magazine into operative position, the transverse intermediate shaft, a hollow fore-and-aft assembler drive shaft geared thereto, a lay shaft geared to the screw, a pair of reversing gears driven constantly from the intermediate shaft, a clutch member geared to the lay shaft and arranged to engage either of said reversing gears, and a hand-controlled rod mounted

in the assembler shaft for operating the clutch member whereby the lay shaft may be connected and disconnected with and from the reversing gears, as desired.

9. In a linotype machine, the combination of a plurality of magazines, a shift frame wherein the magazines are mounted, a screw for raising and lowering the shift frame to bring a selected magazine into operative position, the transverse intermediate shaft, a hollow fore-and-aft assembler drive shaft, a lay shaft geared at its rear end to the screw and having a forward extension axially aligned with the assembler shaft, a reversible gear mechanism for connecting said shaft extension with the intermediate shaft and including a shiftable clutch member, and a hand-controlled rod mounted in the assembler shaft for operating the clutch member, whereby the lay shaft may be connected and disconnected with and from the intermediate shaft, as desired.

10. In a linotype machine, the combination of a plurality of magazines, a shift frame wherein the magazines are mounted, a screw for raising and lowering the shift frame to bring a selected magazine into operative position, the transverse intermediate shaft, a hollow fore-and-aft assembler drive shaft, the intermediate bracket wherein the shafts are journaled, a lay shaft having an inclined portion geared to the screw and a relatively short horizontal portion axially aligned with the assembler shaft adjacent the rear end thereof, and reversible gear mechanism arranged at the rear of said bracket for connecting the lay shaft with the intermediate shaft, said mechanism including a driving gear fast to the intermediate shaft, an oppositely placed gear loose on the intermediate shaft and driven from the assembler shaft, an intermediate clutch member shiftable on the intermediate shaft and geared to the horizontal portion of the lay shaft, and a control rod mounted in the assembler shaft and operable from the front of the intermediate bracket for shifting the clutch member.

11. In a linotype machine, the combination of a plurality of magazines, a shift frame wherein the magazines are mounted, and reversible power operated mechanism for raising and lowering the shift frame to bring a selected magazine into operative position, said mechanism including a positive driving clutch operative when the magazines are raised and a friction clutch operative when the magazines are lowered.

12. In a linotype machine, the combination of a plurality of magazines, a shift frame wherein the magazines are mounted, a screw for raising and lowering the shift frame to bring a selected magazine into operative position, a power shaft, and a reversible gear mechanism for connecting said

power shaft to the magazine shifting screw so as to effect the raising or lowering of the magazines, said mechanism including a pair of oppositely rotating gears and a clutch member shiftable into engagement with one or the other of two gears, said member being formed to make a positive

driving engagement with the magazine elevating gear and a frictional driving engagement with the magazine lowering gear. ¹⁰

In testimony whereof, I have affixed my signature hereto.

ALFRED W. F. GUEST.
